HAIR CURLER

Nathan L. Solomon, Mount Vernon, N. Y.

Application November 30, 1937, Serial No. 177,177

6 Claims. (Cl. 132—33)

The present invention is concerned with an improved and simplified hair curler of the type comprising pivotally associated clamping components adapted to grip a portion of a tress of hair which is wound about the complements upon bodily rotation of the curler about its longitudinal axis to form a curl and one object of the invention resides in the provision of stop means to prevent displacement of the clamped portion 10 of the tress towards the fulcrum means pivotally sustaining the complements thus precluding shearing of the hair when interposed between and clamped by the clamping components, and another object of the invention is realized in the provision of a serviceable hair curler wherein one of the components embodies a shoulder and a reduced portion, the shoulder cooperating to limit pivotal displacement of the companion complement or cover of the curler while the reduced 20 portion constitutes a tine which in association with the cover defines relatively elongated gap means in which a part of the tress is initially clamped preparatory to forming a curl and subsequently readily withdrawn therefrom upon removal of the formed curl from the curler. Other objects, advantages and features of the invention will appear from the following detailed description considered in connection with the accompanying drawing, in which—

30 Fig. 1 is a perspective view of the hair curler according to my invention, showing a portion of a tress of hair interposed between the companion complements preparatory to being clamped thereby.

35 Fig. 2 is a longitudinal view of the curler showing the complements closed and about which a curl has been formed.

Fig. 3 is a longitudinal sectional view of the curler in a normally closed relation.

40 Fig. 4 is a sectional view on the line 4—4 of Fig. 3, and

Fig. 5 is an exploded and perspective view of the complements.

The hair curler 10 comprises complementary 45 hair clamping components 11 and 12. Component 11 in part includes a tubular cylindrical portion characterized by a shoulder or brace sleeve 13 and the reduced portion 14 which in effect constitutes a tine. Component 12 may be said to be 50 a hollow inverted U-shaped cover or tine and includes perforated depending lugs 16 straddling tube or component 11 at the rear of shoulder 13.

With the cover 12 mounted on component 11 55 the perforations 17 of lugs 16 are in line with

perforations 18 of component 11. Thereafter a ferrule or rivet 19 is inserted into the aligned perforations and upset at its ends as shown to prevent displacement of the complements or components 11 and 12 longitudinally of the ferrule which serves as fulcrum means permitting the complements to be pivotally opened as shown in Fig. 1 upon moving manipulating portions 20 towards each other and of course the complements may be pivotally closed upon removing of 10 finger pressure from manipulating portions 20 and due to action of spring 21 the complements are normally held closed.

In Fig. 1 a portion 22 of a tress of hair is mounted on tine 14 of complement 11. Thereafter 15 finger pressure on the part of the operator is removed. Consequently tine or cover 12 closes. This portion 22 is held clamped between the tines 12 and 14. In this connection, it will be observed that stop shoulder 13 prevents shifting 20 of hair longitudinally of the curler towards the fulcrum means. It should also be observed that with the cover closed aligned gaps 25 are formed defined by the sides of the cover and lower tine 14. Although the tress is initially clamped when 25 traversing these gaps the latter permits ease of removal of this clamped part of the tress upon removal of the curl from the curler and since the forward part of the cover 12 and tine 14 do not overlap, the edges thereof even though the 30 curler is closed cannot cut the hair interposed between the tines. In other words, the aligned gaps 25 constitute a relief to facilitate the removal of the curl without danger of shearing a part of the curl as often occurs if the sides of 35 the cover were in overlapping relation with the sides of its companion complement as in the case of that portion of the cover above shoulder 13 and since the clamped part of the curled tress is prevented from reaching the part of the curler above shoulder 13 shearing of the tress is prevented.

In the broader aspects of the invention, I do not desire to be understood as limiting its embodiments to details herein described and shown 45 illustratively as a wide variety of modifications may be made within the scope of the appended claims without departing from the spirit of the invention.

50 I claim:

1. In a curler, a pair of complementary clamping members, means pivotally sustaining said members, one of said members comprising a tubular portion and a reduced portion defining a 55

- 5 tine, the other member of said pair constituting a cover, said reduced and tubular portions defining a shoulder to limit pivotal displacement of said cover towards said tine, said cover and tine defining elongated gaps constituting relief means to permit withdrawal of hair from said curler in a closed relation of the latter.
- 10 2. In a curler, complementary hair clamping members, fulcrum means pivotally supporting said members, one of said members comprising elongated means having a shoulder and an elongated tine, another of said members constituting a cover and defining with said tine alined elongated gaps, spring means for holding said curler closed, said shoulder in the fully closed relation of said curler defining means to limit pivotal displacement of said cover towards said tine.
- 15 3. In a curler, complementary hair clamping members, fulcrum means pivotally supporting said members, one of said members defining elongated means having a shoulder and an elongated tine, another of said members constituting a cover, spring means for holding said members closed, said members in the closed relation thereof defining alined gaps, said cover and tine adapted to clamp a portion of hair interposed therebetween, said shoulder constituting means to prevent displacement of said clamped portion of hair towards said fulcrum means in a closed relation of said members.
- 20 4. In a curler, complementary hair clamping members, fulcrum means pivotally supporting said members, one of said members comprising elongated means having a shoulder and an elongated tine, another of said members constituting

a cover and defining with said tine alined elongated gaps, spring means for holding said curler closed, said shoulder in the fully closed relation of said members defining means to limit pivotal displacement of said cover towards said tine.

5 5. In a curler, complementary hair clamping hollow members, fulcrum means pivotally supporting said members, one of said members defining elongated means having a shoulder disposed forwardly of said fulcrum means and an elongated tine arranged forwardly of said shoulder, another of said members constituting a cover, spring means for holding said members closed, said members in the closed relation thereof defining alined gaps, said cover and tine adapted to clamp a portion of hair traversing said gaps, said shoulder constituting means to prevent displacement of said clamped portion of hair towards said fulcrum means.

10 6. A hair curler comprising two elongated members substantially semi-circular in cross section, said members having end portions formed to provide operating handles, one of said members adjacent to its operating handle being constructed to provide an elongated brace sleeve, means for pivotally connecting the members one to the other at a point rearwardly of but closely adjacent to the brace sleeve, contact of the second member with the brace sleeve limiting the extent of movement of the members one toward the other, said sleeve when in contact with the second member being snugly received therein, and means for constantly urging said members to said limit of movement.

NATHAN L. SOLOMON.
